STEEL RETAINER

Edward F. Terry, Phillipsburg, N. J., assignor to
 Ingersoll-Rand Company, New York, N. Y., a
 corporation of New Jersey

Application October 14, 1939, Serial No. 299,402

4 Claims. (Cl. 279—19.5)

This invention relates to rock drills, and more particularly to a retainer for preventing ejection of a working implement from a rock drill of the type in which the working implement and the percussive element actuating it are capable of reciprocatory movement independently of each other.

One object of the invention is to equip the rock drill with a retainer of simplified and rugged construction and which will permit of the working implement being expeditiously inserted into and removed from the rock drill.

Other objects will be in part obvious and in part pointed out hereinafter.

In the drawing accompanying this specification and in which similar reference numerals refer to similar parts,

Figure 1 is an elevation, partly in section, of the front end portion of a rock drill equipped with a retainer constructed in accordance with the practice of the invention.

Figure 2 is a transverse view taken through Figure 1 on the line 2—2, and

Figure 3 is a perspective view of the retainer.

Referring more particularly to the drawing, 20 28 designates, in general, a rock drill of which only a front head 21 and a portion of a cylinder 22 are shown as casing parts.

The front head 21 and the cylinder 22 may be secured together in any well known manner, and in the front head 21 is a cavity 23 into which the nose of the hammer piston 24, reciprocable in the cylinder 22, moves for delivering blows to a working implement 25 extending through the front head 21 and terminating in the cavity 23.

The bore 26 in the front head 21 through which the working implement 25 extends is only sufficiently larger than the working implement to permit of free slidable movement of the latter, and in one side of the front head 21 and opening into the bore 26 is an aperture 27 to receive a retainer 28 constructed in accordance with the practice of the invention. The aperture 27 is of oblong cross sectional form, having upper and lower semi-cylindrical surfaces 29 which are joined by flatted surfaces 30 tangent thereto.

The aperture which extends from one side to the other of the front head 21 is preferably of uniform cross sectional area throughout its length and is so located that the innermost surface 30 lies closely adjacent the plane of a flat surface 31 constituting the bottom of a recess 32 extending longitudinally of the working im-

plement 25 and being rounded at its ends to form shoulders 33 and 34 at the upper and lower ends, respectively, of the recess. The retainer 28 is of substantially the same cross sectional form as the aperture 27 and is of greater length than the aperture so that its ends project beyond the sides of the front head. It comprises, in the form illustrated, a pair of rigid plates 35 and 36 each having a flat outer surface 37 to seat against a surface 30 of the aperture, and at the ends of the flat surface 37 are rounded surfaces 38 to conform substantially with the curvature of the surfaces 29 of the aperture, and with the shoulders 33 and 34 for which they serve as abutments.

To the end that the retainer may be rendered contractible and expandable in a lateral direction a strip 39 of resilient material, preferably rubber, is interposed between the plates 35 and 36, and suitably bonded to the inner surfaces of the plates to form a unitary structure. The combined thicknesses of the plates 35 and 36 and the rubber strip 39 is somewhat greater than the distance between the flat surfaces 30 of the aperture 27. Thus, when driving the retainer into the aperture the plates may move toward each other as by displacing the rubber which will press the plates outwardly against the flat surfaces 30 and in that way maintain the retainer in firm frictional engagement with the front head.

Preferably the plate 36 is provided with a lateral wing 40 which overlies an end of the strip 39 in the plate 35 and may serve as a stop member for engagement with the side of the front head to prevent the retainer from being placed in an incorrect position in the aperture. Moreover, for the sake of convenience in placing the retainer in the aperture the opposite end 41 of the retainer is bevelled for a short distance to enable it to readily enter the aperture 27.

In practice, the present invention has been found to serve in a highly efficient manner as a retainer for preventing ejection of a working implement from a front head. The retainer may be expeditiously inserted in the retaining position or removed from the front head and when in the retaining position will be held firmly thus by the force of the rubber strip 39 which, being 50 distorted somewhat when inserted into the aperture, will tend to resume its normal form and thereby press the outer surfaces of the plates 35 and 36 against the surfaces of the aperture 27.

A further highly desirable advantage of a retainer constructed in the manner described is

that any one of the rounded surfaces 38 of the plates 35 and 36 may serve as an abutment for the shoulders 33 and 34 and the wear resulting from impact from the shoulders against the retainer may, therefore, be distributed over a wide area.

I claim:

1. A steel retainer for a rock drill having a front head to receive a working implement having a shoulder, an aperture of oblong cross-sectional form in the front head, a retainer in the aperture comprising a plurality of rigid members either of which may serve as an abutment for the shoulder, and a resilient member between the rigid member for maintaining the rigid members in frictional engagement with the wall of the aperture.

2. A steel retainer for a rock drill having a front head to receive a working implement having a shoulder, an aperture of oblong cross-sectional form in the front head, and a retainer in the aperture having a plurality of rounded surfaces each adapted to serve as an abutment

for the shoulder and comprising alternately arranged strips of rigid and resilient material.

3. A steel retainer for a rock drill having a front head to receive a working implement having a shoulder, an aperture of oblong cross-sectional form in the front head, a retainer in the aperture comprising a plurality of rigid members either of which may serve as an abutment for the shoulder, and a resilient member between the rigid member for maintaining the rigid members in frictional engagement with the wall of the aperture.

4. A steel retainer for a rock drill having a front head to receive a working implement having a shoulder, an aperture of oblong cross-sectional form in the front head, and a retainer of greater width than the aperture to lie in said aperture forwardly of the shoulder and having an intermediate resilient zone to permit of lateral contraction and expansion of the retainer, said retainer having a plurality of rounded surfaces each adapted to serve as an abutment for the shoulder.

EDWARD F. TERRY.
